(57) **CLAIM**

The ornamental design for a modular saw horse, as shown and described.

DESCRIPTION

FIG. 1 is a front elevation view of a modular saw horse showing my new design, the opposite side being a mirror image of the shown;

FIG. 2 is a right elevation view thereof, the opposite side being a mirror image of the shown;

FIG. 3 is a top plan view thereof;

FIG. 4 is a bottom plan view thereof;

FIG. 5 is an isometric view thereof; and,

FIG. 6 is an isometric view thereof showing a top beam and a pair of legs separated for clarity.
